ARTICLE FORMING MACHINE

Howard D. Prutton, Cleveland, Ohio, assignor to

Prutton Corporation, a corporation of Ohio

Original application Oct. 4, 1961, Ser. No. 142,967, now Patent No. 3,189,191, dated June 15, 1965. Divided and this application Mar. 19, 1965, Ser. No. 441,126 29 Claims. (Cl. 10—12)

This application is a division of my application Serial No. 142,967, filed October 4, 1961, entitled, "Article Forming," now Patent No. 3,189,191, issued June 15, 1965.

This invention relates to article forming and has for its principal object the provision of improved methods and apparatus for working metal and other materials capable of being formed in dies and by punching or pressing.

An object of the invention is to increase production rates in article forming and to increase the speed with which slugs or blanks may be positioned for forming strokes in the case of relatively long pieces as well as unusually short ones.

A further object of the invention is to simplify the handling and movement of the blanks being worked upon and to enable simplified transfer mechanism to be employed.

Still another object of the invention is to enable the blank to be held relatively stationary while it is being engaged with the die, during the time it is gripped by the transfer mechanism and when it is being released.

Still another object of the invention is to retract the die from a relatively stationary work piece.

A further object is to form both sides or ends of a slug without the necessity for turning it over.

Still another object of the invention is to eject a work piece immediately after it has been formed.

Other and further objects, features and advantages of the invention will become apparent as the description proceeds.

In carrying out the invention in accordance with a preferred form thereof, a blank or piece to be worked upon is positioned and thereafter enveloped in a die while the piece remains substantially fixed in position. Simultaneously therewith the die and a punch or forming head are moved against the piece with sufficient pressure to form the piece. Then the die and punch are retracted while the piece is ejected from the die to maintain the piece substantially fixed in position.

Thereafter, if more than one stroke is required for forming the piece it is transferred to a second working position by moving it along a substantially straight line transverse to the direction of movement of the die and punch to successive working positions bringing it intermittently to rest relative to any lateral movement of the die. Each time the piece is substantially stationary again, relative to lateral die movement, the piece is enveloped in a die and simultaneously therewith the die and a punch are moved longitudinally against the piece with sufficient pressure for further forming the piece. Thereafter each time the die and punch are retracted the piece is ejected from the die to maintain the piece substantially fixed in position until it is fully ejected and ready to be transferred to a further working position.

A better understanding of the invention will be afforded by the following detailed description considered in conjunction with the accompanying drawing, in which:

FIG. 1 is an end elevation of an embodiment of apparatus which may be employed in carrying out the invention;

FIG. 2 is a side elevation of the apparatus of FIG. 1; FIG. 3 is a sequence diagram showing successive por-

2

tions of the rams, transfer fingers and work pieces in a cycle of operation, the different positions being represented in sub-FIGS. 3a to 3f, inclusive;

FIG. 4 is a circular sequence diagram illustrating the operations performed in relation to angular ram positions;

FIG. 5 is a view of a section of the apparatus of FIG. 1 represented as cut by a horizontal plane passing through the center lines of the drive shaft and the ram reciprocating shafts;

FIG. 6 is an elevation of the wire blank feed roll assembly;

FIG. 7 is a view of a section of the feed roll assembly represented as cut by a vertical plane 7—7 indicated in FIG. 6;

FIG. 8 is a fragmentary view of a section of the feed roll assembly represented as cut by a broken plane 8—8 indicated in FIG. 6;

FIG. 9 is an elevation of a disengageable clutch assembly for engaging and disengaging the feed of the feed roll assembly;

FIG. 10 is an elevation of the blank cut-off assembly partially in section represented as cut by a vertical plane 10—10 indicated in FIG. 11;

FIG. 11 is an end elevation of the cut-off assembly;

FIG. 12 is a view of a section of the cut-off assembly represented as cut by a horizontal plane 12—12 indicated in FIG. 11;

FIG. 13 is a fragmentary view of a section of the cut-off mechanism represented as cut by a horizontal plane 13—13 indicated in FIG. 10 and showing the ways for adjustment of the cut-off point;

FIG. 14 is a view of a section of the die ram represented as cut by a vertical plane 14—14 indicated in FIG. 21;

FIG. 15 is a view of a section of the ejector mechanism of FIGS. 5 and 21 represented as cut by a vertical plane 15—15 indicated in FIG. 21;

FIG. 16 is an end elevation of the punch ram or forming ram as seen from the end carrying the forming tools;

FIG. 17 is a side elevation of the punch ram or forming ram;

FIG. 18 is a view of a section of the transfer mechanism of the apparatus of FIG. 1 represented as cut by a vertical plane 18—18 indicated in FIG. 19;

FIG. 19 is a side elevation, represented as seen from the front of the apparatus of FIG. 1, of the transfer mechanism;

FIG. 20 is a top view of the transfer mechanism of FIGS. 18 and 19; and

FIG. 21 is a view of a horizontal section through the die ram and blank ejector mechanism represented as cut by a horizontal plane through the shaft axes indicated by the plane 5—5 in FIG. 1, constituting an enlargement of a portion of the sectional view of FIG. 5.

Like reference characters are utilized throughout the drawing to designate like parts.

An example of suitable apparatus that may be employed in carrying out the article forming methods of the invention is illustrated in FIGS. 1, 2 and 5 to 21 of the drawings, but it will be understood that the article forming invention is not limited to the use of the specific apparatus illustrated in these figures of the drawing.

In carrying out the steps of the process for forming a headed member such as a bolt from wire stock, a length of wire is drawn out from a magazine parallel to the axis of the machine and cut-off to form a blank 11 indicated in FIG. 3d. Before the blank 11 is severed from the stock 12, it is grasped between a first set of fingers 13, 14 and 15 which may constitute the fingers of a transfer mechanism or the jaws of a manually held pair of pliers or the like and is retained substantially unchanged in

location with respect to axial motion during the forming operation, but moved transversely in a substantially straight line to successively different stationary positions for carrying out the forming operations.

It is first brought to a stationary position indicated by dotted lines at 11' in FIG. 3d and simultaneously a die 16 and a punch or article forming tool 17 are moved towards each to cause the die 16 to envelop the blank 11, causing the blank 11 to be supported in the die 16 and to be abutted by the forming tool 17 as shown at FIG. 3e.

Preferably the die 16 and the forming tool or punch 17 are caused to execute counter-rotary movement or to revolve in opposite directions in addition to reciprocating movement as will be described in greater detail hereinafter. In this case, the piece 11 is carried downward as the die 16 and tool 17 approach each other in accordance with the simultaneous downward translation of the members 16 and 17.

When the piece 11 has about reached the position shown in FIG. 3f the fingers 13, 14 and 15 are caused to start separating or opening while the forming members 16 and 17 are moved further toward each other to the position of FIG. 3a to carry out the first step in the forming process of the blank 11, which in the example illustrated constitutes forming a knob 18 thereon which occurs when the forming members 16 and 17 have reached the position shown in FIG. 3a.

The forming members 16 and 17 are then retracted in opposite directions and before the piece 11 has left the die 16 or while the piece 11 is still in the die 16 when the forming members 16 and 17 have separated sufficiently to permit regrasping the piece 11 it is again grasped. This may be done in the same manner as before if desired by the closing of grasping elements or fingers 21, 22 and 23 of the same type as the fingers 13, 14 and 15.

The piece 11 is then ejected from the die 16 at the same rate as the die 16 is retracted to the left so that the piece 11 does not move axially, although in the case of forming members 16 and 17 having the revolving motion previously alluded to, it is moved slightly transversely in accordance with the movement of the forming members 16 and 17. As the forming members 16 and 17 separate further, the piece 11 which is now carrying the knob 18 is moved onward transversely towards the next forming location represented at 19 in FIG. 3e.

If a transfer mechanism is employed, it will not be the fingers 13, 14 and 15 which grasp the piece 11 after the knob 18 has been formed thereon, but the second set of fingers 21, 22 and 23 in order to leave the fingers 13, 14 and 15 free for grasping and transferring a second blank from the cut-off position to the station of forming members 16 and 17, the fingers 21, 22 and 23 serving to transfer the blank 11 from the station of forming members 16 and 17 to the station of a second set of forming members including, for example, a die 24 and a punch or forming tool 25.

It is to be understood, however, that the invention is not limited to placing the die on one side and the punch or forming tool on the other side in successive stations as the positions may be alternated if desired according to the operations to be performed on the blank which is to be formed, thus avoiding the necessity for turning over the piece or the blank in moving to successive stations when the formation of the piece requires working upon opposite sides or ends thereof in succession.

It will be understood that there are one or more stations at which the article is subjected to forming operations according to the form that it is desired that the article take and the nature of the material, hardness, plasticity and so forth, which is being worked upon. By way of example the article forming method is described as carried out when it is worked upon in three successive stations. Thus, the second station is that of the die 24 and the punch or

forming tool 25 which are designed for flattening the knob 18 to form a bolt head 26 on the piece 11.

The cycle of operations for a single revolution of the rams carrying the forming members is the same as before.

5 In the next cycle of operations an additional blank is cut-off and carried through the movements described for the blank 11. The blank 11, however, now referred to as the blank in position 19 is enveloped in the die 24 as the forming members approach each other from the position shown in FIG. 3d to that shown in FIG. 3f whereupon the fingers 13, 14 and 15 and 21, 22 and 23 open and move out of the way to permit the forming members to approach each other to reach their final position shown in FIG. 3a at which the head 26 is completely formed.

15 As soon as the forming members have retracted the distance represented by FIG. 3b the pieces are again grasped. If a transfer mechanism is employed the fingers 13, 14 and 15 will have closed at about the position shown in FIG. 3b for grasping a third blank, the fingers 21, 22 and

20 23 will have reached the position shown in FIG. 3b for grasping the second blank and a third set of fingers 27, 28 and 29 are grasping the blank 11 in order to hold it in a fixed position with respect to longitudinal movement as it is simultaneously ejected from the die 24 as the die

25 24 recedes therefrom to enable the blank to be carried laterally as indicated in FIG. 3d to the station 30 of forming members 31 and 32 which may be a die 31 and a trimming tool 32 which completes the formation of the head 26 for a purpose, for example, of cutting off the corners 30 to form a hexagonal head 33 as the members 31 and 32 travel successively through the positions represented by FIG. 3d, 3e, 3f and back to the position of FIG. 3a.

The form of apparatus shown by way of example in FIGS. 1 and 2 comprises a base 34 carrying a motor 35 and supporting a framework 36 for mounting the bearings for a main shaft 37, a die ram shaft 38 and a punch ram shaft 39 (shown in FIG. 5).

The main shaft 37 is connected to the motor 35 in a suitable manner as by means of V-belts 41 connecting a motor pulley 42 and a fly wheel pulley 43 on the shaft 37. Preferably for protecting the machine, a fawick clutch-brake combination represented generally by the reference numeral 44 is interposed between the fly wheel 43 and the shaft 37. The clutch-brake combination, however, not being a part of the present invention, but being conventional in form is not described herein. Suitable gearing, including gears 45, 46, 47 and 48, is provided for connecting the main shaft 37 to the ram drive shafts 38 and 39.

50 As indicated generally in FIGS. 1 and 2, various auxiliary mechanism is also mounted upon the base 34 or the framework 36 including a wire stock feed roll assembly 49 and a transfer mechanism 51, retractable as will be described more fully hereinafter for enabling the dies or ram tools to be interchanged or adjusted. As shown in FIG. 2, provision is made for driving the feed roll assembly 49 from the die ram crank shaft 38 by means of a connecting rod 52.

55 As shown more clearly in FIG. 5, there is a die ram 53 supported at both ends by eccentrics and a punch ram 54 likewise supported at both ends by eccentrics so that both rams remain horizontal at all times but execute rotary motion or such a motion that each part thereon revolves about some horizontal axis with the two rams 60 revolving in opposite directions so that they simultaneously execute reciprocating motion toward or away from each other and likewise up and down motion in unison. The die ram 53 is supported at one end by an eccentric 55 on the crank shaft 38 and at the opposite end it is guided by an eccentric 56 carried by a shaft 57 which in turn carries the gear 46 meshing with the drive gear 47 of the main shaft 37. Idler gears, not shown, are provided between gears 45 and 46, and between gears 47 and 48, to obtain revolving movement of the rams 53 and 54 with both rams remaining horizontal. The punch ram

54 is in like manner supported at the outer end by an eccentric 58 on the crank shaft 39. At the inner end the ram 54 is guided by an eccentric 59 on the main drive shaft 37.

The die ram 53 also carries an ejector mechanism including ejector push rods 61, 62 and 63 (FIG. 14). The ram 53 has a die face 64. The punch ram 54 carries suitable clamping mechanism 65 for mounting the forming tools, punches or the like 17, 25 and 32, which are shown in flat-faced form for simplicity in FIGS. 2 and 5. For actuating the ejector mechanism including the ejector push rods 61, 62 and 63, a cam 67 is mounted on the die ram crank shaft 38.

In order that the alignment of the rams 53 and 54 may be adjusted and possible wear on the parts may be compensated so that the rams 53 and 54 will always remain horizontal, roller bearings 68 and 69 may be mounted on the rams 53 and 54, respectively, for receiving the eccentric journals 56 and 59, respectively, and provided with adjustable mounting blocks 71 and 72 fastened to rams 53 and 54, respectively, as shown in FIG. 5.

As shown in FIGS. 6 and 7, the feed roll assembly 49 comprises a pair of feed rolls 73 and 74 with grooves 75 in their peripheries for gripping wire stock 12 from a magazine (not shown) and feeding the wire stock 12 to a cut-off mechanism 77 (shown in FIGS. 3 and 11).

There is a drive for the feed rolls 73 and 74 comprising a ratchet crank 78 connected by a shank 79 of connecting rod 52 to the die ram driving crank shaft 38 adjustably by means of a T-slot 81 and bolt 82 engaging a shouldered nut 83 in the T-slot 81. The bolt 82 and nut 83 are so arranged that when the nut 82 is tightened it clamps the nut 83 in a predetermined position in the slot 81 and also secures a post 84 upon which the rod 52 is pivoted. A spring connection 85 may be included in the connecting rod 52 if desired.

The crank 78 is connected to the shaft 86 of the feed roll 74 by means of a one-way or back stopping clutch 87. The arrangement is such that the crank 78 engages the shaft 86 when the connecting rod 52 is drawn to the right but releases when the rod 52 is pushed to the left. The invention is not limited to the use of any particular ratchet mechanism or one-way clutch and the details of the one-way clutch 87 need therefore neither be illustrated or described. Satisfactory results have been obtained, however, by the employment of a one-way Marquette type clutch described in the 1959 printed catalogue of Curtiss-Wright Corporation, Marquette Division, Cleveland, Ohio, entitled, "Curtiss-Wright Clutches."

The feed roll 73 is mounted upon a shaft 88 connected to the shaft 86 by means of gears 89 and 90. Preferably a back stopping clutch 92 is mounted on the shaft 88 and secured to the feed roll assembly housing 93 for preventing backward rotation of the shaft 88 on the idle stroke of the crank 78. The back stopping clutch 92 may be a marquette clutch of the same type as the clutch 87. A toggle clamp 94 is provided for releasably clamping the feed roll 73 against the feed roll 74 upon the wire 76.

The clutch 87 is provided with an ear (not visible in FIG. 7) for engaging a pawl 91, on a member 95. A clutch control lever 96 is provided for retracting the pawl 91 on the member 95 beyond the normal stroke of the ear on the clutch 87 to permit the machine to function and the feed rolls to operate. The arrangement is such, however, that when the lever 96 is released to take the position represented by the dotted lines 96', the pawl 91 engages the ear on the clutch 87 for applying enough pressure to the clutch 87 through a spring 97 to prevent the clutch 87 from operating. In this manner, the feed of the feed rolls can be engaged and disengaged. The force of the spring 97 is greater than the force required to retain the ear on the clutch 87 and therefore through the use of the spring 97 the clutch 87 can be disengaged in the back position of the stroke no matter what the adjustment is in the T-slot 81.

As illustrated in FIGS. 10, 11, 12 and 13, the cut-off mechanism 77 comprises a tube 101 through which the feed rolls 73 and 74 are adapted to push the wire stock 12, a screw 102 aligning the end of the tube 101, a cut-off quill 103 having a hardened bushing 104 therein, a feed stop 105 and a cut-off knife 106. The quill units 103 and 104 are mounted in an adjustable frame 107 and are adjustable in a line parallel to the axis or pressure application line of the machine. The feed stop 105 is adjustably mounted upon the frame 107 by means of a slotted base bracket 108 and machine screws 109. In this manner, the cut-off piece 11 can be approximately centralized with the transfer mechanism so that the transfer fingers 13, 14 and 15 can grasp the blank 11 in the center.

15 A rotary cam mechanism is provided for actuating the cutter knife 106. This comprises an arm 111 rotatable about a post 112, a cam surface 113 on the side of the arm 111 toward the end thereof and a mating cam surface 114 on the end or back edge of the knife 106. A thrust bearing 115 is preferably provided to take up the lateral thrust of the cam surfaces 113 and 114. The screw 102 serves for adjusting the clearance between the cut-off quill 103, 104 and the cut-off knife 106. The pivot post 112 upon which the arm 111 oscillates is put in such a position that the screw 116 and the head on the post 112 can be preloaded to handle the forces required to cut-off the wire 12.

The cut-off knife 106 is provided with a hub-portion 117 pivoted by a screw 118 and a flanged journal 119. 30 A limit stop for the knife 106 is provided comprising a surface 121 co-operating with an adjustable screw 122. A spring (not shown) is preferably provided for holding the knife 106 down against the cam surface 114 and the limit stop screw 122.

35 The operation of the cut-off 77 is such that the center line of the wire 12 is approximately $\frac{1}{8}$ of an inch below the center line of the transfer fingers 13, 14 and 15 and when the part is cut it is pushed up into the transfer fingers which are then adapted to transfer it into the machine.

40 For oscillating the cut-off arm 111, a slotted block 123 is provided which is secured to the die ram 53 by machine screws 124, which causes the block 123 to rotate with the die ram. The arm 111 is provided with blocks 125 adapted to slide in slots 126 formed in a channel shaped portion 127 of the member 123. Thus, the blocks 125 reciprocate as the die ram 53 revolves to communicate vertical oscillatory motion to the cut-off arm 111.

45 Longitudinal adjustment of the frame 107 of the cut-off assembly 77 upon the upright portion 128 of the machine framework 36 is provided by means of bolts 129 co-operating with horizontally elongated slots 131 in the upright 128. Preferably the frame 107 is notched at 132 to fit over ways 133 with end abutments 134 serving as limit stops for the adjustment of the frame 107.

50 FIGS. 14, 15 and 21 illustrate a sub-assembly of the die ram and ejector mechanism. The tools 16, 24 and 31 are shown as cylindrical pieces of steel with holes therein to conform to the work. The tools are shown as 55 cylindrical for the sake of simplicity and may represent, for example, the tools for the forming of a common fastener. As already explained, the cut piece of wire which is to be formed is held in front of the die 16. Because of a rotary motion of the die ram 53 the die 16 envelopes the cut piece 11 until the punch 17 begins to push it and then the fingers on the transfer mechanism open.

60 The ejector mechanism comprises a sliding member 135 carrying a cam follower 136 co-operating with the cam 67 on the die ram drive shaft 38 and a plurality of levers 137, 138 and 139, which co-operate with ejector rods 61, 62 and 63, respectively. Co-operating with the ejector rods 61, 62 and 63 are ejector pins 141, 142 and 143 which, in turn, co-operate with ejectors 144, 145 65 and 146, respectively.

For making minor adjustments in length of the working area of the dies 16, 24 and 31, wedges 147, 148 and 149 are provided which co-operate with bevel ended heads 151, 152 and 153 of the ejector pins 141, 142 and 143, respectively. Springs 154 are provided for keeping the ejector slide 135 against the cam 67. A bump 155 is formed on the cam 67 and the ejector pin 143 is made slightly longer, for example, $\frac{1}{16}$ inch longer than the ejector pins 141 and 142 such that only the ejector pin 143 is actuated by the bump 155 on the cam 67. This is done for the purpose of giving a slight push in the final station to finish the shearing operation of the trim as close to bottom dead center as possible. Springs 156 surround the ejector pins 141, 142 and 143 to urge the heads 151, 152 and 153 into engagement with the wedges 147, 148 and 149.

For adjusting the wedges 148, locking screws 157 may be provided having locking members 158 secured by lock screws 159. A pivot rod 161 is provided for the levers 137, 138 and 139. Shear pins 162 are provided so that if an exceptionally heavy load is required to eject the work piece the shear pin 162 breaks and no damage is caused to the machine.

As shown in FIGS. 16 and 17, the punch ram 54 carries tools 17, 25 and 32 which are shown with flat faces for convenience, although these may take the form of dies or punches as desired. If one or more of the forming tools 17, 25 or 32 is in the form of a die for enveloping the work an ejector slide mechanism similar to that illustrated in FIGS. 14 and 21 will be provided. For example, in a nut former, in order to avoid reversing the part alternately to apply the work force to opposite sides or alternate sides, the tools will alternately be punches and dies. An ejector in the punch ram 54 then also serves the purpose of ejecting pieces from the punch to insure that they remain in the die ram for the timed ejection into the transfer fingers.

In the embodiment illustrated, the punches 17, 25 and 32 are held in punch blocks 163 and held in place by wedging clamping bolts 164, wedging sleeves 165 and nuts 166. For longitudinal adjustment suitable wedges are provided actuated by adjusting screws 167. For vertical positioning there are wedges 168, screws 169 and T-nuts 170. Horizontal alignment is provided by studs 171 and nuts 172. Locking plates 173 with fastening screws 174 serve for holding in place the screws 167 which effect the longitudinal wedge adjustment of forming tools 17, 25 and 32.

The transfer mechanism 51 shown in greater detail in FIGS. 18, 19 and 20 is provided with a drive shaft 176 connected to the die ram 53 by means of a crank 177 and a pin 178 fitting within a socket 179 in the die ram 53. The throw of the pin 178 is the same as that of the eccentrics 55 and 56 so that the motion of revolution of the die ram 53 is communicated to the transfer mechanism shaft 176. There is a cam shaft 181 connected to the drive shaft 176 by a pair of bevel gears 182 and 183.

The cam shaft 181 and associated parts driven thereby are carried in a framework 184 pivotally secured to the machine framework 36 by means of a vertical pintle 185 carried in brackets 186.

The cam shaft 181 carries three cams 187, 188 and 189. Co-operating with the cam 187 is a cam follower 191 on an arm 192 having a slot 193 at the end co-operating with a pin 194 carried by an upper slide 195. The slide 195 carries the first set of transfer fingers 13, 14 and 15 for carrying the blank 11 down to the first die 16. The fingers 13, 14 and 15 are mounted on the slide 195 separate from the other transfer fingers because of the longer distance of travel for this set of fingers to carry the piece 11 from the cut-off mechanism 77 to the first die 16.

Co-operating with the cam 188 is a cam follower 196 mounted on a bent arm 197 pivoted at one end receiving a pivot pin 198 and having a slot 199 at the opposite end co-operating with a pin 201 fixed in a lower slide 202.

The lower slide 202 carries the remaining sets of transfer fingers, namely, the second set 21, 22 and 23 and the third set 27, 28 and 29. The peripheral shape of the cams 187 and 188 is such that the blank 11 is carried from the cut-off station 77 to the position of the first die 16 taking into consideration the circular motion of the die and punch rams, and that the blank ejected from the die 16 is carried from the station of the die 16 to the die 24 also taking into consideration the circular motion of the rams. Since the distance between the dies 24 and 31 is the same as that between the dies 16 and 24, the sets of fingers for accomplishing the transfer from one die to the next may be carried upon the same slide 202.

The third cam 189 is provided for opening and closing the fingers 13, 14, 15, 21, 22, 23, 27, 28 and 29. To this end a cam follower 203 is provided which co-operates with the cam 189 and is carried at the elbow of an elbow lever 204 pivoted at one end upon a pivot pin 205. Pivotally secured to the opposite end of the lever 204 is an adjustable link 206 having pivot pins 207 and 208 at opposite ends thereof. Preferably a biasing spring 209 is connected to the end of the lever 204 carrying the pivot pin 207 for holding the cam follower 203 against the periphery of the cam 189.

The pivot pin 208 in the link 206 is mounted in a swinging plate or bell crank block 211 pivotally secured to a stationary pivot pin 212. There is a corresponding bell crank 213 pivotally secured to a stationary pivot pin 214. Interconnecting the bell cranks 211 and 213 is an adjustable link or rod 215 having pivot pins 216 and 217 at the ends in the bell cranks 211 and 213, respectively.

Mounted in the bell cranks 211 and 213 are also pivot pins 218 and 219 secured in ears 221 of a plate 222 having a vertical groove 223 therein. The arrangement is such that as the cam 189 rotates causing the cam follower 203 to rise and fall the vertically grooved plate 222 moves to and fro primarily with a horizontal component of motion, moving to the left and to the right as seen in FIG. 19.

To co-operate with the vertical groove 223 in the horizontally moving plate 222 are cam followers 224, 225, 226, 227, 228 and 229, horizontal movement of which serves for opening and closing the fingers 13, 14, 15, 21, 22, 23, 27, 28 and 29. The vertical groove 223 may, if desired, to be given a special shape for modifying the action of the fingers.

The transfer fingers are in the form of bell cranks. The pair of fingers 13 and 15 have a pivot 231 on the sliding plate 195 with a bell crank arm 232 carrying the cam follower 224, likewise the transfer finger 14 has a pivot 233 on the upper slide 195 with a bell crank arm 234 carrying the cam follower 225. The pivot fingers 21, 22, 23, 27, 28 and 29 are constructed in a similar manner but mounted upon the lower slide 202. Preferably the opening and closing of the transfer fingers is effected in timed relation to the circular motion of the rams 53 and 54.

The mounting of the entire transfer mechanism 51 upon the pintle 185 permits the transfer mechanism 51 to be swung out of the way when the tools 16, 24 and 31 and 17, 25 and 32 are to be worked upon or changed. When the transfer mechanism 51 is swung out, the bevel gears 182 and 183 separate to disengage the power from the transfer mechanism. The gears 182 and 183 are marked so that when the transfer mechanism 51 is re-engaged the sequence of operation is in the proper timing. Wing nuts 235 co-operating with swinging bolts 236 pivoted to the frame at the inner end are provided for securing the transfer mechanism 51 in operative position. In order to realign the transfer mechanism in relation to the machine, very accurately tapered plugs 237 are secured to the swinging framework 238 of the transfer mechanism 51 adapted to mate with tapered seats 239.

The sequence of operation is indicated in the diagrams of FIG. 3 and in FIG. 4. In FIG. 4 the clockwise movement of the die ram drive shaft or cam shaft 38 is represented, with zero degrees representing bottom dead center

with rams 53 and 54 closed and 180 degrees representing top dead center with the rams opened. FIG. 3a represents the zero degree position, FIG. 3b the 45 degree position, FIG. 3c the 90-degree position, FIG. 3d the 180-degree position, FIG. 3e the 270-degree position and FIG. 3f the 315-degree position. During the first 45 degrees of rotation of the die ram cam shaft 38 and likewise of the driving pin 178 and the drive shaft 181 of the transfer mechanism 51, the transfer fingers are open. The opening action has begun at the 315 degree position of the previous stroke so that the transfer fingers are open and out of the way while the forming tools are close to each other.

The transfer fingers are caused to close at some point during the first 90 degrees, for example, at the 45 degree position so that the blank will be held by the transfer fingers when it has been cut-off and in like manner the blanks which have previously been worked upon will be held preparatory to transfer to the next station. At the 90-degree position cut-off of the stock 12 takes place to form the blank 11. From the 90-degree to the 270-degree point the fingers 13, 14 and 15 are moved from the cut-off mechanism 77 to alignment with the die 16 but the transfer fingers 21, 22, 23, 27, 28 and 29 remain stationary. From the 270-degree to the 315-degree position all the transfer fingers move and all open at about the 315-degree position. From the 315-degree to the 45-degree point all the transfer fingers again are open and work is done on the blanks between the 315-degree position and the bottom dead center or zero degree position.

The wire feed takes place during the 180 degrees of motion from top dead center to bottom dead center, that is, from 180 degrees position to zero or 360 degrees position. Cut-off of a new blank again takes place at the 90-degree position so that the operation is repeated, each blank being advanced one position for each rotation of the die ram drive shaft 38. The bump 55 on the ejector cam shaft 67 gives an extra push to the ejector pin 143 when the bump strikes the cam follower 136 at the 90 degree position so that the trim of the head 26 is completed and the finished piece may be discharged when the fingers again open.

While the invention has been described as embodied in concrete form and as operating in a specific manner in accordance with the provisions of the patent statutes, it should be understood that the invention is not limited thereto, since various modifications will suggest themselves to those skilled in the art without departing from the spirit of the invention.

What is claimed is:

1. A metal working machine comprising in combination a pair of rams, each adapted to carry first and second cooperating metal working tool means, means for moving the rams oppositely in circular paths, whereby the rams alternatively approach each other and recede from each other for working upon a piece by said first tool means during the approach stroke of the rams, and transfer means to transfer a piece laterally from said first to said second tool means during the period of separation of said rams for subsequent working on the piece by said second tool means.

2. Apparatus as in claim 1, wherein said transfer means are provided for positioning a work piece between the rams substantially fixed in position with respect to motion parallel to the line joining the centers of rotation of the rams.

3. Apparatus as in claim 1, wherein each ram is provided with a tool face having successive stations and said transfer means are provided for carrying a piece to be worked upon substantially in a line transverse to the line joining the centers of rotation of the rams for performing successive forming operations upon the work piece at a high rate of speed by utilizing a minimum of time in the transfer of the piece from one work station to another.

4. A metal working machine comprising a pair of lon-

gitudinally extending rams extending substantially in alignment, a tool face on each ram, means on one of said ram tool faces to engage and partially envelop a work-piece, and each ram having a pair of eccentrics for supporting it with the eccentrics so arranged for maintaining the rams substantially in alignment as each of the tool faces on the rams executes circular motion to relatively move the two tool faces longitudinally toward each other along a pressure application line and to simultaneously move a workpiece transversely of the pressure application line.

5. Apparatus as in claim 4, wherein a stock feed is provided beside one of the rams with means driven in accordance with a ram for cutting off successive pieces of stock, and means feeding said pieces laterally to the lines of motion of the rams to successive positions between the rams for performing successive forming operations thereon.

6. In a metal working machine for applying forming pressure substantially in the direction of a predetermined line referred to as the line of pressure application, a ram having a longitudinal axis parallel to said pressure application line, a working face on said ram, means on said working face to partially envelop and support a work-piece, and means for revolving the ram about an axis of revolution transverse to the longitudinal axis and reciprocating the ram with its longitudinal axis remaining parallel to the line of pressure application to move said working face and a workpiece therein with a component parallel to said line of pressure application and also with a component perpendicular to said line of pressure application.

7. In a metal working machine for applying forming pressure in opposite directions substantially parallel to a predetermined line referred to as a line of pressure application, a pair of rams, each having a longitudinal axis parallel to said pressure application line, said rams being in alignment with each other, means on one of said rams to support a workpiece, and means for revolving the rams in opposite directions about axes of revolution transverse to the longitudinal axes and reciprocating the rams oppositely with longitudinal axes remaining parallel to the line of pressure application and in alignment with each other to relatively move the two rams toward each other along said line of pressure application and to simultaneously move a workpiece supported on said one of said rams transversely of said line of pressure application.

8. Apparatus as in claim 7, including means for transferring a workpiece from a position beside the rams along a line transverse to the line of pressure application and between the rams while the rams are spaced apart and holding the work piece at rest between the rams relative thereto while the rams are executing the portions of their strokes in which the rams are spaced most closely together.

9. Apparatus as in claim 8, wherein each ram is provided with a tool face having a plurality of stations, the stations of one ram tool face corresponding to those of the other and the work piece transfer means is provided with means for holding the work piece at rest relative to the rams at each station in succession while the rams are in the proximity portions of their strokes and transferring the work piece to successive stations while the rams are in the spaced apart portions of their strokes.

10. In a metal working machine having a ram with a longitudinal axis and means for revolving the ram about an axis of revolution transverse to the longitudinal axis and reciprocating the ram with its longitudinal axis remaining parallel to itself in successive positions, a stock cut-off mechanism comprising a cut-off actuator secured to the ram and having a slot therein extending parallel to the longitudinal axis of the ram, a cutter arm having a fixed pivot axis at one end and a follower at the opposite end engaging said slot, whereby the cutter arm is oscillated around said pivot axis by the revolution of said

ram, and a cutter knife actuated by oscillation of said cutter arm in a plane transverse to said longitudinal axis of said ram.

11. Apparatus as in claim 10, wherein the cutter arm carries a cam face at the pivoted end thereof and the cutter knife is moveably mounted with a cam follower surface adapted for actuation by said cam face.

12. Apparatus as in claim 11, wherein the cam face at the pivoted end of the cutter arm is helical and the direction of motion of the cutter knife is parallel to the pivot axis of the cutter arm, the pivot axis of the cutter arm being parallel to the axis of revolution of the ram.

13. Apparatus as in claim 10, including a transfer mechanism, means for ejecting the cut-off stock into the transfer mechanism when the cutter knife is at the end of its cutting stroke and means for thereafter moving the transfer mechanism in a plane perpendicular to the longitudinal axis of the ram.

14. In a metal working machine for applying forming pressure substantially in the direction of a predetermined line referred to as the line of pressure application, having a ram with a longitudinal axis parallel to said pressure application line and means for revolving the ram about an axis of revolution transverse to the longitudinal axis and reciprocating the ram with its longitudinal axis remaining parallel to the line of pressure application, a transfer mechanism having work gripping means and means for mounting the transfer mechanism moveably along a line transverse to the pressure application line and transverse to the axis of revolution of the ram with the line of motion of the work gripping means being beyond the end of the ram, and cam means driven by the ram for reciprocating the transfer mechanism with alternating periods of reciprocating motion and rest relative to said pressure application line during each revolution of the ram.

15. In a metal working machine for applying forming pressure substantially in the direction of a predetermined line referred to as the line of pressure application, having a ram and means for reciprocating the ram parallel to the line of pressure application, a transfer mechanism having work gripping means and means for mounting the transfer mechanism moveably along a line transverse to the pressure application line with the line of motion of the work gripping means being beyond the end of the ram, and cam means for reciprocating the transfer mechanism with alternating periods of reciprocating motion and rest relative to said pressure application line during each reciprocation of the ram.

16. Apparatus as in claim 15, wherein the gripping means constitute pivoted fingers with operating levers extending transversely to the line of pressure application with track followers at the ends of the operating levers, a transversely moveable track for receiving the operating lever followers, means for maintaining the track parallel to the direction of motion of the transfer mechanism and transverse to the line of pressure application, whereby movement of the transfer mechanism along its line of motion has no effect on the work gripping fingers with respect to opening or closing them, and means for moving the track laterally and in a direction transverse to said line of pressure application while the transfer mechanism is in its position of rest relative to said pressure application line for alternately releasing and regripping work pieces prior to and subsequent to forming strokes thereon.

17. A transfer mechanism for a machine having drive means reciprocating a ram for working upon blanks, said transfer mechanism comprising a shaft, crank means driven from said drive means to rotate said shaft in unison with the moving ram, a first cam on said shaft, a cam follower and linkage actuated by said cam for moving a blank from a cut-off position to a first working station, a second cam on said shaft, a cam follower and linkage actuated by said second cam for moving blanks successively from the first working station to successive work-

ing stations, a third cam on said shaft, and a cam follower and linkage actuated by said third cam for grasping work in transfer from one position to the next and releasing it upon positioning the work.

18. Apparatus as in claim 17, including a sliding plate actuated by said first cam follower and linkage, the sliding plate being moveable between said cut-off and first working station positions.

19. Apparatus as in claim 18, including a second sliding plate moveable the distance between working stations and actuated by the second cam follower and linkage.

20. Apparatus as in claim 19, including transfer fingers mounted upon the sliding plates and in which the linkage of the third cam follower is connected to the fingers for opening and closing them.

21. Apparatus as in claim 20, wherein the sliding plates are vertically moveable and the transfer fingers have bell crank arms with said cam followers at the ends thereof and the cam follower linkage of the third cam includes a plate having a vertically extending groove engaging the cam followers of the transfer fingers, the vertical-groove plate having a horizontal component of motion produced by the third cam follower linkage and the bell crank arms of the transfer fingers extend normally at a small angle to the vertical whereby the horizontal motion of the vertical-groove plate causes rotation and opening and closing movement of the transfer fingers.

22. Apparatus as in claim 14, including a working station on said ram, and said cam means moves said transfer means to move a work blank transversely of said pressure application line during at least the initial engagement of said work blank with said working station.

23. Apparatus as in claim 22, including said cam means moving said transfer means transversely of said pressure application line during at least the initial pickup of said work blank from said working station.

24. In a forging machine having a punch ram and die ram relatively counter-rotationally moveable toward and away from each other and simultaneously moveable in a first direction a given distance on a transverse path to work on a workpiece and move same on said path, said rams having first and second punches and first and second dies spaced apart on said path approximately said given distance, the improvement of transfer means moveable along said path, said transfer means including transfer fingers, cam and follower means acting on said transfer fingers to open and close same on any said workpiece, said cam and follower means moving in said first direction and relatively slowly and grasping and holding said workpiece during movement of same in said first direction and during release of the workpiece from said first punch and die and moving said workpiece only in said first direction a distance less than half said given distance to a position whereat said workpiece is held in said second punch and die and then releasing said transfer fingers.

25. In a forging machine having a punch ram and die ram relatively counter-rotationally moveable toward and away from each other and simultaneously moveable in a first direction a given distance on a lateral path to work on a workpiece and move same transversely on said path, said rams having first and second punches and first and second dies spaced apart on said path approximately said given distance, the improvement of transfer means moveable along said path, said transfer means including transfer fingers, cam and follower means acting on said transfer fingers to open and close same on any said workpiece and to move said fingers only along said path and less than half said given distance to transfer a workpiece from said first to said second punch and die.

26. In a forging machine having a punch ram and die ram relatively counter-rotationally moveable toward and away from each other and simultaneously moveable in a first direction a given distance on a lateral path to work on a workpiece and move same transversely on said path, said rams having first and second punches and first and

second dies spaced apart on said path approximately said given distance, the improvement of transfer means moveable along said path approximately only 30% of said given distance and including transfer fingers closeable on any said workpiece in said first punch and die at about a 45-degree position from the longitudinal axis of said punch and die ram, means to hold said transfer fingers closed for about another 270 degrees of rotation of said punch and die rams and to then open said transfer fingers at about the 315-degree position whereat said workpiece is enveloped in said second punch and die.

27. In a forging machine having a punch ram and die ram relatively counter-rotationally moveable toward and away from each other simultaneously moveable in a first direction a given distance on a transverse path to work on a workpiece and move same on said path approximately 70% of said distance, said rams having first and second punches and first and second dies spaced apart on said path approximately said given distance, the improvement of transfer means moveable along said path approximately only 30% of said given distance and including transfer fingers closeable on any said workpiece in said first punch and die at about a 45-degree position from the longitudinal axis of said punch and die ram, cam means to hold said transfer fingers closed and to move same transversely in said first direction approximately 15% of said given distance to about a 90-degree position and to maintain said fingers closed and stationary for about another 180 degrees to the 270-degree position, and said cam means moving said transfer fingers transversely in said first direction approximately 15% of said given distance to about a 315-degree position of said rams whereat said workpiece is enveloped in said second punch and die and then opening said fingers.

28. A forging machine, comprising, in combination, a base, a punch ram and a die ram on said base, means to move each said punch ram and die ram in a counter-rotational movement for relative longitudinal movement toward and away from each other for working on a workpiece and for simultaneously moving said rams laterally in a first direction a given distance on a path to move said workpiece transversely on said path approximately 70% of said distance, first and second punches on said punch ram and first and second dies on said die ram, said first and second punches and said first and second dies being spaced apart transversely on said path approximately said given distance, and transfer means moveable in said path approximately 30% of said given distance and including transfer fingers closeable on any said workpiece in said first punch and die at about a 45-degree position from the longitudinal axis of said punch and die ram, and means to hold said transfer fingers closed for about another 270 degrees of rotation of said punch and die rams and to then open said transfer fingers at about the 315-degree position whereat said workpiece is enveloped in said second punch and die.

being spaced apart transversely on said path approximately said given distance, and transfer means moveable in said path approximately 30% of said given distance and including transfer fingers closeable on any said workpiece in said first punch and die at about a 45-degree position from the longitudinal axis of said punch and die ram, cam means to hold said transfer fingers closed and to move same transversely in said first direction approximately 15% of said given distance to about a 90-degree position and to maintain said fingers closed and stationary for about another 180 degrees to the 270-degree position of said rams, and said cam means moving said transfer fingers transversely in said first direction approximately 15% of said given distance to about a 315-degree position of said rams whereat said workpiece is enveloped in said second punch and die and then opening said fingers.

29. A forging machine, comprising, in combination, a base, a punch ram and a die ram on said base, means to move each said punch ram and die ram in a counter-rotational movement for relative longitudinal movement toward and away from each other for working on a workpiece and for simultaneously moving said rams laterally in a first direction a given distance on a path to move said workpiece transversely on said path approximately 70% of said distance, first and second punches on said punch ram and first and second dies on said die ram, said first and second punches and said first and second dies being spaced apart transversely on said path approximately said given distance, and transfer means moveable in said path approximately 30% of said given distance and including transfer fingers closeable on any said workpiece in said first punch and die at about a 45-degree position from the longitudinal axis of said punch and die ram, and means to hold said transfer fingers closed for about another 270 degrees of rotation of said punch and die rams and to then open said transfer fingers at about the 315-degree position whereat said workpiece is enveloped in said second punch and die.
